UNITED STATES PATENT OFFICE.

GLENN WALTER GOODMAN, OF MEMPHIS, TENNESSEE

GUARD FOR RAILROAD CROSSINGS.

Application filed November 9, 1923. Serial No. 673,824.

To all whom it may concern:

Be it known that I, GLENN WALTER GOODMAN, a citizen of the United States, and a resident of Memphis, in the county of Shelby and State of Tennessee, have invented certain new and useful Improvements in Guards for Railroad Crossings, of which the following is a specification.

This invention relates to that class of apparatus which guards the approach of highways at railroad grade crossings and has for its object the provision of a device caused to be operated by a moving train and disposed in the path of the grade crossing to prevent vehicles from reaching the tracks.

A further object of the invention is the provision of a device automatically operated to obstruct grade crossings and equipped with an automatic time release for causing a removal of the obstruction in the event that the train does not reach the grade crossing within a predetermined time.

Another object of the invention is the provision of a device for positioning an obstruction transversely of the railway grade crossing to not only act as a warning but prevent traffic at the crossing by throwing an obstruction across the road bed with automatic means for causing the obstruction to be removed after the train has cleared the crossing.

A still further object of the invention is the provision of a device automatically operated by the wheels of a train for placing obstructions in the path of the traffic to warn travellers of the approach of a train but permitting vehicles in close proximity to the obstruction and travelling at a high rate of speed to proceed across the obstruction without interference and at a time when the train is substantially $\frac{1}{4}$ mile from the grade crossing, the obstruction being sufficiently elevated after this point to prevent actual crossing.

Another object of the invention is the provision of a device forming an obstruction to traffic at grade crossings and controlled by fluid pressure through the direct action of the wheels of the train upon a pumping mechanism.

This invention will be best understood from a consideration of the following detailed description, in view of the accompanying drawing forming a part of the specification; nevertheless it is to be understood that the invention is not confined to the dis-

closure, being susceptible of such changes and modifications which shall define no material departure from the salient features of the invention as expressed in the appended claims.

In the drawings:

Figure 1 is a plan view of the tracks and grade crossing showing my invention applied in operative position.

Figure 2 is a transverse vertical section taken along the line 2—2 of Figure 1.

Figure 3 is a longitudinal vertical section of the bumper and its related parts forming obstructions to traffic at a grade crossing.

Figure 4 is a vertical section of the fluid pumping mechanism operated by the wheels of a passing train.

Figure 5 is a plan view of the pumping mechanism shown in Figure 4.

Figure 6 is a vertical section of the release valve box for controlling the return of the bumper.

Figure 7 is a plan view of the device shown in Figure 6.

Referring more particularly to the drawings, 1 designates each of a pair of rails of a railroad track and 2 the highway which crosses the rails at a grade crossing 3.

At predetermined distances from the crossing 3 and transversely of the highway and upon opposite sides of the track are provided pits 3^a which are cut into the roadbed having its side walls and bottom formed of a concrete construction 4 or any other material suitable for the purpose.

A beam 5 is connected with the side walls of the pit and is provided with a rod 6 upon which is pivotally mounted a curved arm 7 having a forward extension 8 to which is rigidly secured a bumper plate 9. The arm 7 has a portion extended substantially parallel to the plate 9 and below the beam 5 and has a weight or counter-balance 10 mounted upon its free end. The upper end 11 of the beam is cut away as shown at 11 to permit free oscillation of the curved arm 7.

The forward free end of the bumper 9 is provided with a depending transparent member 12 which is adapted to normally seat within the pit 3^a and adjacent the end wall 13 of said pit and to be carried upwardly or downwardly by the bumper 9. The transparent member 12 is red in color and its surface is such that it is adapted to reflect the sunlight during the day and the artificial light directed upon it at night in

order to warn travellers along the highway of the position of the bumper and likewise of the approach of a train.

A pair of cylinders are located adjacent the forward end of the pit 3^a and rigidly mounted upon the bottom of the same in each of which is adapted to reciprocate a piston 15. Rods 16 have pivotal connections with the pistons 15 and with the inner wall of the bumper 9. A fluid feed line 16^a is connected with the cylinders 14 below the pistons 15 and adapted to supply fluid under pressure for elevating or lowering the pistons and likewise elevating or lowering the forward end of the bumper 9.

A box or casing 17 is placed in a pit between the ties of the railroad track and adjacent the rail 1. A pair of these casings are disposed a predetermined distance from the grade crossing 3. A rock shaft 18 is mounted in bearings within the casing and is provided with a rock arm 19 having pivotal connections with a rod 20 which has its other end connected to a piston 21 mounted for operation within a cylinder 22. Said cylinder is mounted upon the bottom of the casing 17.

A dash pot comprising a cylinder 23, a piston 24 is connected to the shaft 18 by means of a rod 25 and a rock arm 26.

A crank arm 27 has a bumper roller 28 adapted to be engaged by the wheels of the trains and depressed for oscillating the crank 27 and rocking the shaft 18. The roller 28 is disposed adjacent the rail 1, as shown more particularly in Figure 4.

Cylinder 22 is directly connected by means of a pipe line 29 and branch pipes 30 to the pipes 16^a which are in communication with the bottom of the cylinders 14 which cooperate with pistons 15 for controlling the elevation of the bumper 9.

A time release 31 located in the casing 17 and in pipe line 29 is adapted to relieve pressure of the fluid in the cylinder 22 and thereby permit the piston 21 to descend at a predetermined time. This time release acts after the train has operated the crank 27 to raise the bumper 9 and where the train has failed to continue to the crossing. This permits the disappearing bumper 9 to be returned to its horizontal position and in line with the top of the road bed in those cases where the trains are withheld from movement between the position of the casing 17 and the crossing 3 in order that the traffic may continue which otherwise would be held up indefinitely.

The casings 17 are supplied with oil which is the fluid employed for operating the pistons 21 and an inlet valve 32 provides communication between the bottom of the cylinders 22 and the casings 17. A poppet valve 33 of usual construction is connected with cylinder 22 and is adapted to permit the oil

to escape from the cylinder when pressure of the oil is increased beyond a predetermined degree in order to prevent injury to the mechanism.

A closed casing 34 is located in a pit between the rails 1 and to one side of the grade crossing 3 and is adapted to provide means for releasing the pressure in cylinder 22 and permitting the bumpers to descend and disappear within the upper end of their respective pits 3^a. This casing is provided with a shaft 35 having a crank 36 which is adapted to be operated through a roller 37 being engaged by an element of the moving train. This roller is located adjacent a rail. The shaft 35 is provided with a rock arm 38 connected to a piston 39 by means of a rod 40. Said piston is adapted to reciprocate within a cylinder 41 mounted upon the bottom of the casing 34. The piston 39 and cylinder 41 cooperate to form a dash pot to prevent sudden action of certain of the elements of the mechanism and which will be presently explained.

A second rock arm 42 is rigidly connected with the shaft 35 and operated thereby for operating a crank 43 connected to the arm 42 by a rod 44. The crank operates a release valve diagrammatically shown at 45. The valve is connected by means of a pipe 46 with the pressure line 29 for releasing pressure on the pistons 21 and permitting the pistons to descend after the train has left the grade crossing.

A pipe 47 is connected to a pipe 48 which connects the pairs of casings 17 located upon opposite sides of the grade crossing 3 and is adapted to provide an equalizing line between the various casings.

As shown more particularly in Figure 2, a pair of cylinders 14 and cooperating pistons 15 are located in each pit 3^a which carry the disappearing bumpers and are both connected to the pressure pipe 30.

The operation of my device is as follows:

The rollers 28 are always maintained in an elevated position and adapted to be engaged by some element on the moving train whereby the same is depressed, causing rocking of the shaft 18. The piston 21 is then forced downwardly into the cylinder 22 forcing the oil out of said cylinder through the pipe lining 29 and into the pipes 30 to the bottoms of the cylinders 14 and through the conduit 16^a which is in communication with said cylinders below the pistons 15. The casings containing the operating mechanism which includes the piston 21 and the cylinders 22 are located at approximately $\frac{1}{4}$ of a mile from the crossing and when the train operates the rock shaft 18 and depresses piston 21 the first impulse of the fluid acting upon the piston 15 will elevate said piston and likewise the forward ends of the bumpers 9 about three inches. The

dash pot, including the cylinder 23 and the piston 24, prevents any sudden action of the piston 21 on the fluid in the system and which may cause injury to the mechanism. 5 The slight elevation of approximately three inches of the forward end of the bumper 9 will permit any vehicle which is travelling at a high rate of speed along the highway to pass over the partially elevated bumper and 10 prevent sudden stopping of the vehicle whereby the vehicle may clear the grade crossing without subjecting the occupants of the vehicle to any danger from the train.

After the train has reached at least approximately $\frac{1}{4}$ of a mile from the crossing, an equilibrium in the fluid pressure line has been reached and the bumper will have been elevated approximately five more inches which locates the free end of the bumper at 15 about eight inches above the road bed and will prevent passage of vehicles onto the grade crossing, but not off of the grade crossing.

In order to prevent a continuous operation of the crank arm 27 by the moving train, the crank arm, together with the roller 28 is maintained out of its normal position and located horizontally through the action of the piston 24 and in the cylinder 23 which operates as a dash pot and overcomes the pressure of the fluid in the lines from returning the piston 21 from its position of upstroke until after a predetermined time which is sufficient to permit the 20 train to entirely pass over the arm before the same begins to return to its elevated position.

In order to cause lowering of the bumpers 9 after the train has cleared the grade crossing 3, I have provided the casing 34 located upon one side of the crossing and between the rails 1 so that as the train reaches the grade crossing 3 the crank arm 36 will be operated together with the arms 42 and 38 connected with the shaft 35. The 25 operation of rock arm 42 operates the valve 45 and opens the pressure line 46 and permits the oil below the pistons 15 in the cylinders 14 to flow back into casing 17. The arm 38 operates the piston 39 in cylinder 41 which comprises the dash pot to prevent sudden action of the elements of the mechanism and with a consequent injury to the parts.

The time release 31 may be of any approved type and is designed to permit the fluid from the cylinders 22 to flow back into the casing 17 and permit the pistons 21 to descend for lowering the bumpers 9 at a time when the train after having actuated the pistons 21, fails to reach the crossing for some reason and continue its passage.

If desired or necessary a pair of casings may be disposed adjacent each other having separate pumping mechanism together with

a separate crank arm adapted to be operated by the moving train for increasing the pressure upon the fluid which operates the piston 15 and likewise the bumpers 9.

The pipe 48 connecting the casings 17 located upon opposite sides and at a considerable distance from the grade crossing 3 is adapted for the purpose of equalizing pressure between said casings and the casing 34. The poppet valve 33 is provided to relieve 75 pressure within the cylinder 22 when the pressure in said cylinder exceeds a predetermined degree.

What I claim is:

1. A guard for railroad crossings comprising a bumper adapted to be elevated across a highway, operating means connected with the bumper for raising said bumper above the highway, a pump located in the path of a moving train, pipes carrying a fluid and connecting the pump with the elevating means for the bumper, a crank arm adapted to be actuated by the moving train for operating the pump and supplying pressure to the fluid in the pipes for 80 setting the elevating means in action to raise the bumper, and means for causing limited elevation of the bumper when the pump is actuated but permitting subsequent elevation of the bumper. 95

2. A guard for railroad crossings comprising a bumper adapted to be elevated across a highway, operating means connected with the bumper for raising said bumper above the highway, a pump located 100 in the path of a moving train, pipes carrying a fluid and connecting the pump with the elevating means for the bumper, a crank arm adapted to be actuated by the moving train for operating the pump and supplying pressure to the fluid in the pipes for 105 setting the elevating means in action to raise the bumper, and means to maintain the crank arm out of engagement with the moving train after the arm has been moved 110 to an operative position, and means for causing limited elevation of the bumper when the pump is actuated but permitting subsequent elevation of the bumper.

3. A guard for railroad crossings comprising a bumper adapted to be elevated across a highway, operating means connected with the bumper for raising said bumper above the highway, a pump located 115 in the path of a moving train, pipes carrying a fluid and connecting the pump with the elevating means for the bumper, a crank arm adapted to be actuated by the moving train for operating the pump and supplying pressure to the fluid in the pipes for 120 setting the elevating means in action to raise the bumper, and means actuated by the moving train for causing release of pressure in the pipes to permit return of the bumper, and means for causing limited eleva- 125

tion of the bumper when the pump is actuated but permitting subsequent elevation of the bumper.

4. A guard for railroad crossings comprising a bumper adapted to be elevated across a highway, operating means connected with the bumper for raising said bumper above the highway, a pump located in the path of a moving train, pipes carrying a fluid and connecting the pump with the elevating means for the bumper, a crank arm adapted to be actuated by the moving train for operating the pump and supplying pressure to the fluid in the pipes for setting the elevating means in action to raise the bumper, means actuated by the moving train for causing release of pressure in the pipes to permit return of the bumper, and means to prevent immediate relief of the pressure, and means for causing limited elevation of the bumper when the pump is actuated but permitting subsequent elevation of the bumper.

5. A guard for railroad crossings comprising a bumper adapted to be elevated across a highway, operating means connected with the bumper for raising said bumper above the highway, a pump located in the path of a moving train, pipes carrying a fluid and connecting the pump with the elevating means for the bumper, a crank arm adapted to be actuated by the moving train for operating the pump and supplying pressure to the fluid in the pipes for setting the elevating means in action to raise the bumper, means to maintain the crank arm out of engagement with the moving train after the arm has been moved to an operative position, and means to release the pressure on the elevating means at a predetermined time after the pump has been actuated by the moving train and when the train has failed to reach the crossing.

6. A guard for railroad crossings comprising a bumper adapted to be elevated across a highway, operating means connected with the bumper for raising said bumper above the highway, a pump located in the path of a moving train, pipes carrying a fluid and connecting the pump with the elevating means for the bumper, a crank arm adapted to be actuated by the moving train for operating the pump and supplying pressure to the fluid in the pipes for setting the elevating means in action to raise the bumper, means actuated by the moving train for causing release of pressure in the pipes to permit return of the bumper, and means independent of the last mentioned means for releasing pressure in the pipes after a predetermined time to permit return of the bumper.

7. A guard for railroad crossings comprising a bumper adapted to be elevated across a highway, a cylinder, a piston op-

erating therein and connected with the bumper, a pump remotely located from the bumper, operating means connected with the pump and adapted to be actuated by the moving train, pipes carrying a fluid and connecting the pump with the cylinder, said pump when actuated adapted to force the fluid through the pipes under pressure and cause movement of the piston for elevating the bumper, and means for causing limited elevation of the bumper when the pump is actuated but permitting subsequent elevation of the bumper.

8. A guard for railroad crossings comprising a bumper adapted to be elevated across a highway, a cylinder, a piston operating therein and connected with the bumper, a pump remotely located from the bumper, operating means connected with the pump and adapted to be actuated by the moving train, pipes carrying a fluid and connecting the pump with the cylinder, said pump when actuated adapted to force the fluid through the pipes under pressure and cause movement of the piston for elevating the bumper, a valve, operating mechanism adjacent the bumper adapted to be operated by the moving train for relieving pressure in the pipes to permit return of the bumper, and means for causing limited elevation of the bumper when the pump is actuated but permitting subsequent elevation of the bumper.

9. A guard for railroad crossings comprising a bumper adapted to be elevated across a highway, a cylinder, a piston operating therein and connected with the bumper, a pump remotely located from the bumper, operating means connected with the pump and adapted to be actuated by a moving train, pipes carrying a fluid and connecting the pump with the cylinder, said pump when actuated adapted to force the fluid through the pipes under pressure and cause movement of the piston for elevating the bumper, a valve, operating mechanism adjacent the bumper adapted to be operated by the moving train for actuating the valve to relieve pressure in the pipes to permit return of the bumper, casings enclosing the cylinder and piston and the valve, and pipes connecting the casings for equalizing the pressure within said casings.

10. A guard for railroad crossings comprising a bumper adapted to be elevated across a highway, a cylinder, a piston movable in the cylinder and connected with the bumper, a casing remotely located from the bumper, a pump located within the casing, means projecting from the casing adapted to be operated by the moving train for actuating the pump, a casing located adjacent the bumper, a valve within the casing, a pipe carrying liquid and connected between the pump and the cylinder whereby fluid

- under pressure is forced within the cylinder for actuating the piston and raising the bumper, an equalizing pipe connecting the casings, a pipe connecting the first mentioned pipe with the valve, and means adapted to be operated by the moving train for operating said valve to relieve pressure in the first mentioned pipe and permit the bumper to lower.
- 10 11. A guard for railroad crossings comprising a bumper, a casing carrying said bumper, a bar mounted in the casing, said bumper being pivotally connected at one end to the bar, said bumper forming a closure for the upper end of the casing, a counter-weight connected to the bumper and suspended below the same and movable within the casing, and means operated by a moving train for elevating the free end of the
- 15 20 bumper above and transversely of the highway.
12. A guard for railroad crossings comprising a bumper, a casing carrying said bumper, a bar mounted in the casing, said bumper being pivotally connected at one end to the bar, said bumper forming a closure for the upper end of the casing, a counter-weight connected to the bumper and suspended below the same, and movable within the casing, means operated by a moving train for elevating the free end of the bumper above and transversely of the highway, and a reflecting member connected with the bumper and adapted to be withdrawn when the free end of the bumper is elevated and operating as a warning signal to traffic.
13. A guard for railroad crossings comprising a bumper adapted to be elevated across a highway, operating means connected with the bumper for raising said bumper above the highway, a pump located in the path of a moving train, pipes carrying a fluid and connecting the pump with the elevating means for the bumper, a crank arm adapted to be actuated by the moving train for operating the pump and supplying pressure to the fluid in the pipes for setting the elevating means in action to raise the bumper, and means connected with the pump for checking elevation of the bumper, said means permitting further elevation of the bumper after a predetermined lapse of time.
14. A guard for railroad crossings comprising a bumper adapted to be elevated across a highway, operating means connected with the bumper for raising said bumper above the highway, a pump located in the path of a moving train, pipes carrying a fluid and connecting the pump with the elevating means for the bumper, a crank arm adapted to be actuated by the moving train for operating the pump and supplying pressure to the fluid in the pipes for setting the elevating means in action to raise the bumper, a cylinder, a piston movable in the cylinder adapted to be influenced by the liquid under pressure for checking elevation of the bumper at the time that the train operates the crank arm but permitting further elevation of the bumper after a predetermined lapse of time.

GLENN WALTER GOODMAN.
